UNITED STATES PATENT OFFICE.

JUNIUS SCHENCK AND BENJAMIN L. STOWE, OF BROOKLYN, ASSIGNEES, BY DIRECT AND MESNE ASSIGNMENTS, TO THE EUREKA FIRE HOSE COMPANY, OF NEW YORK, N. Y.

SEAMLESS MULTIPLY-FABRIC HOSE.

SPECIFICATION forming part of Letters Patent No. 299,018, dated May 20, 1884.

Application filed October 17, 1883. (No model.)

To all whom it may concern:

Be it known that we, JUNIUS SCHENCK and BENJAMIN L. STOWE, of Brooklyn, Kings county, New York State, have invented a certain new and useful Improvement in Seamless Multiply Tubular Hose, of which the following is a specification.

Our invention is an improvement upon seamless multiply woven hose for fire, hydraulic, and other purposes, of the kind shown and described in Reissued Letters Patent No. 7,442, dated December 19, 1876; and it consists in the novel construction or combination of parts hereinafter fully set forth and claimed, whereby we enhance the capacity of this hose to resist tendency to elongation under heavy pressure, such as it is necessarily subjected to when used as fire hydraulic hose in connection with steam fire-engines.

The nature of our improvement, and the manner in which the same is or may be carried into effect, will be readily understood by reference to the accompanying drawings, in which—

Figure 1 is a cross-section of our improved hose, only one-half of the tube being represented. Fig. 2 is a longitudinal section on line 2 2, Fig. 1.

In the actual web or fabric the strands are of course packed closely together. In the drawings, however, they are represented on enlarged scale, and as widely separated from one another, in order that the structure of the multiply fabric may be more plainly seen and understood. The seamless multiply tubular fabric which forms the body of the hose is in this instance a three-ply fabric, the warps and wefts of the two outer plies of which, as well as the tying-strands, are manipulated in the manner illustrated and described in Reissued Letters Patent No. 7,442. The warp-strands of the outermost ply are lettered *a*, and the weft-strands *b*. The warp-strands of the intermediate or second ply are lettered *c*, and the weft-strands *d*. The tying-strands, which pass through the web from face to face, are lettered *e*. The inner or third ply of the web differs from the corresponding ply of the

fabric hose described in said Reissued Letters Patent No. 7,442, in that the warp-strands (lettered *f*) of this ply, instead of being interlocked or interwound with their weft, (lettered *g*), as in the other plies, are so manipulated as to lie straight and without material bend or corrugation between the second ply and the inner weft-threads, *g*, which latter are held in position by the tying-strands *e*, the two being interwound or interwoven with one another in the manner described in said Reissued Letters Patent. The warp-strands *f* are preferably put under considerable tension during the weaving operation, so as to insure their being laid straight and without bend. We thus obtain a multiply seamless hose of the type described in said Reissued Letters Patent, which contains a layer of straight longitudinal strands held in place between the inner weft and the next adjoining ply, and serving effectively to prevent any perceptible or material elongation of the hose.

Hose possessing the foregoing characteristics can be readily manufactured by the method and apparatus set forth in the Reissued Letters Patent No. 7,442, with such modifications thereof required for the purpose as are within the knowledge of those skilled in the art to which our improvement relates.

The hose, after being woven, is provided with a rubber lining, *h*, applied to it in well-known manner. This lining, when in place, serves materially to assist in holding the inner weft and adjoining strands in place, thus fixing and holding the fabric and assuring the position of the longitudinal strands *f*.

We do not here claim, broadly, a multiply seamless woven hose having straight longitudinal strands incorporated therewith, so as to prevent elongation of the hose, for this we have made the subject of another application for Letters Patent of even date herewith.

What we claim as new and of our invention is—

1. Seamless multiply woven hose in which the outer ply or plies, tying-strands, and inner weft-strands are combined with straight longitudinal strands laid and held between the

inner weft-strands and the adjoining ply, substantially as and for the purposes hereinbefore set forth.

2. Seamless multiply woven hose consisting of outer ply or plies, tying strands, and inner weft-strands, combined with straight longitudinal strands laid between the inner weft-strands and the next adjoining ply, and the rubber lining, which, by its adhesion to the fabric, serves to assist in holding the strands

in position, substantially as hereinbefore set forth.

In testimony whereof we have hereunto set our hands this 1st day of September, A. D. 1883.

JUNIUS SCHENCK.
BENJAMIN L. STOWE.
